PACKAGING MACHINE

Robert W. Saumsiegle, Lexington, and Ralph L. Wing, Burlington, Mass., assignors to Pneumatic Scale Corporation, Limited, Quincy, Mass., a corporation of Massachusetts

Filed Mar. 8, 1962, Ser. No. 178,412
19 Claims. (Cl. 53—189)

This application is a continuation-in-part of Serial No. 105,458, filed April 25, 1961.

This invention relates to a packaging machine.

The invention has for an object to provide a novel and improved packaging machine particularly adapted for opening successive flat envelope type bags and inserting articles therein in a simple, rapid and efficient manner.

With this general object in view and such others as may hereinafter appear, the invention consists in the packaging machine and in the various structures, arrangements and combinations of parts hereinafter described and particularly defined in the claims at the end of this specification.

In the drawings illustrating the preferred embodiment of the invention:

FIG. 1 is a side elevation partly in cross section of a packaging machine embodying the present invention;

FIG. 2 is a plan view of the machine showing the upper portion thereof;

FIG. 3 is a plan view of the machine with the upper portion removed and showing the driving mechanism;

FIG. 4 is an end view as seen from the right of FIG. 1 showing the intake end of the machine;

FIG. 5 is an end view as seen from the left of FIG. 1 showing the delivery end of the machine;

FIG. 6 is a side elevation of the article advancing mechanism and supporting tray to be referred to;

FIG. 7 is an end view of the same as seen from the line 7—7 of FIG. 6;

FIG. 8 is a side elevation partly in cross section of the bag opening and article inserting mechanism showing an article in position to be inserted into the open bag;

FIG. 9 is a detail view in side elevation of a modified form of the bag opening mechanism;

FIG. 10 is a plan view of the same;

FIG. 11 is a view similar to FIG. 8 showing the article fully seated in the bag;

FIG. 12 is a plan view detail of the bag;

FIG. 13 is a cross sectional view of the same taken on the line 13—13 of FIG. 12;

FIG. 14 is a plan view of the bag opening and article inserting mechanism;

FIG. 15 is a front view of the article inserting mechanism as seen from the line 15—15 of FIG. 11;

FIG. 16 is a detail view of a separable driving connection for the inserting member;

FIG. 17 is a view in side elevation of the inserting driving mechanism;

FIG. 18 is an end view of the same;

FIG. 19 is a detail of a portion of the driving mechanism shown in FIG. 17 in a different position of operation;

FIG. 20 is a detail view of the elevating mechanism associated with the delivery conveyer;

FIG. 21 is a side elevation of a modified arrangement of the article advancing mechanism;

FIG. 22 is a side elevation of a further modified form of bag opening mechanism including a modified form of a magazine for supporting a stack of bags;

FIG. 23 is a detail view of the modified form of bag

2

opening mechanism shown in FIG. 22 and showing a portion of the bag magazine;

FIG. 24 is an end view of the bag opening mechanism and bag magazine shown in FIG. 22;

FIG. 25 is a plan view of a portion of the bag opening mechanism shown in FIG. 22; and

FIG. 26 is a side elevation of a modified form of the article advancing mechanism to be described.

In general the present invention contemplates a novel packaging machine particularly adapted for opening flat envelope type bags, inserting articles therein and transferring successive filled bags onto a discharge conveyer for delivery to a subsequent machine, not shown, for trimming and sealing the mouths of the filled bags. The illustrated machine is adapted to insert articles of merchandise into flat bags of relatively thin, transparent sheet plastic material, such as polyethylene sheet material, and the articles of merchandise to be packaged may have considerable thickness, the illustrated articles comprising a bakery product, such as a group of connected rolls, inserted as a unit into the bag.

In the illustrated embodiment of the invention a stack of flat plastic bags is supported in a magazine, and provision is made for opening the mouth of the uppermost bag and expanding or inflating the bag by means of a stream of air which maintains the bag in its open condition while the article to be packaged is inserted therein. The mouth portion of the illustrated bag is provided with an extended flap along one wall, herein shown as the lower wall of the flap bag, leaving the upper edge of the mouth portion exposed to be lifted and expanded by the stream of air directed thereagainst, and provision is made for gripping and temporarily retaining in the magazine the extended portion of the lower wall of the mouth portion during the bag opening operation. In most instances a stream of air directed against the exposed edge of the mouth of the bag is sufficient to lift the upper wall of the flat bag to permit air to enter between opposed walls of the bag to inflate the same. However, in a modified form of the invention air operated means is provided for first mechanically separating the upper wall from the lower wall of the bag along a small portion of the mouth to permit air to enter between the walls to expand the bag. While the bag is thus held in its open position provision is made for rocking a pair of opposed mouth spreading and article guiding arms within the mouth of the bag to engage and hold the open end of the bag in its spread open condition to receive the article to be packaged. Successive articles to be packaged are moved into operative relation to an article inserting member movable longitudinally of the machine which is arranged to engage the article and advance the same between the spreader arms and into the bag. A longitudinally movable tray which also enters the bag is arranged to support the article therein, and in operation continued movement of the tray and the inserting member serves to pull the retained end of the bag out of the magazine, pull the mouth of the bag off the mouth spreading and article guiding means and deliver the filled bag onto the discharge conveyer in one continuous operation. Thereafter, the spreader arms are contracted, and the supporting tray and inserting member are retracted to their initial positions in readiness for a succeeding cycle of operation.

Provision is also made in the illustrated embodiment of the invention for moving successive articles into operative position to be engaged by the inserting member, an article being moved into such operative position during a portion of the preceding cycle. Control means is also provided for detecting the presence of an article in position to be engaged by the inserting member and for discontinuing operation of the machine at the end of a cycle.

of operation in the event that an article has failed to be advanced into position to be inserted during such cycle. Provision is also made for discontinuing operation of the machine when a stack of bags in the magazine is depleted, and also for discontinuing operation of the machine in the event that an article is delivered to the conveyer without a bag.

Referring now to the drawings, 10 represents a stack of flat plastic bags supported in a magazine which may include a vertically movable platform 12 detachably secured to a stack supporting and elevating unit indicated generally at 14. The bags are retained on the platform 12 by an inverted U-shaped retainer 16, the vertical legs of which extend through spaced openings 17 provided in an extended flap portion 18 of the bag. As shown in detail in FIGS. 12 and 13, each bag is provided with an upper wall or ply 20 and a lower wall or ply 22, the flap 18 extending from the lower wall 22 as shown. The horizontal leg of the U-shaped retainer 16 bears against the top of the stack, and the vertical legs extend loosely through the platform 12 and through a downwardly bent extension 24 thereof. The closed end of the bag is provided with a gusseted portion 26, and the outer end of the platform 12 is downwardly inclined, as shown to compensate for the relatively thicker 4-ply gusseted ends of the bags. The stack supporting and elevating unit 14 is arranged to urge the stack upwardly, and a stationary hooked member 28 extended over the horizontal leg of the retainer 16 is arranged to maintain the top of the stack at a constant level as successive uppermost bags are withdrawn from the stack.

The stack supporting and elevating unit 14 includes a head portion 30 provided with opposed inwardly bent retaining plates 32 forming a grooved track. The underside of the platform 12 is provided with a pair of angle bars 34 arranged to be fitted into the grooved track to detachably secure the platform to the head portion 30 for convenience in replacing a platform, from which the bags are depleted, with a loaded platform. The head portion 30 is supported at the upper ends of a pair of spaced vertical rods 36, only one of which is shown, and which are slidably supported in spaced brackets 38 secured to an upright bar 40. The bar 40 is secured by bolts 41 to a portion of the machine frame. Provision is made for resiliently urging the slide rods 36 upwardly with a substantially constant tension and, as herein shown, the lower ends of the rods are connected by a tie bar 42 through which the end of a cord 44 is extended and secured. The cord 44 is guided around a pulley 46 mounted on a stud secured to a plate 48 extended from the upright bar 40, and the cord then extends into a recoil unit indicated generally at 50 supported on a stud 52 carried by a bracket 54 extended from and secured to the upright bar 40. The recoil unit 50 may comprise any of the conventional commercially available types of such units, which are spring loaded to apply tension to the cord whereby to move the stack upwardly as successive bags are withdrawn from the stack. It will be noted that the U-shaped retaining member 16 remains stationary against the hooked member 28 as the platform moves up, the latter sliding on the vertical legs thereof. Provision is also made for locking the head portion 30 in its lowered position for convenience when a loaded platform is to be detachably secured to the head portion. As herein shown, the head portion is provided with an opening 56 into which the rounded end of a spring pressed rod 58 may be fitted when the platform is in its lowered position. The rod 58 is mounted to slide in an opening provided in a bracket 60 secured to the upright bar 40 by bolts 62. The outer end of the rod 58 is provided with a handle 64, and in operation when the rod is pulled outwardly the elevating unit is released to urge the stack upwardly as described.

It will be observed that the bags are retained in the stack by their flap portions 18, leaving the upper edge or mouth portion of the upper wall 20 exposed, and pro-

vision is made for expanding the bag by means of a stream of air arranged to enter under the upper wall while the bag is retained in the stack by the retaining member 16. While the stream of air directed against the exposed edge of the upper wall is sufficient in most instances to lift the upper wall and to expand the bag, in a modified form of the invention provision is made for initially lifting the upper wall slightly to break the adherence of the upper wall to the lower wall of the bag at the mouth thereof so as to provide an opening therebetween to admit air. As herein shown, see FIGS. 9 and 10, the mouth opening means may comprise a curved leaf spring 65 extended from a supporting plate 68 and having a coiled end portion 70 arranged to extend above the front edge of the upper wall. Cooperating with the leaf spring 65 is a flexible flapper 72 also secured to and extended from the supporting plate 68 and which extends above and in engagement with the upper surface of the leaf spring. The flapper 72 and the curved leaf spring 65 normally extend above the front edge of the upper wall, and in operation when a stream of air is directed under the supporting plate and under the flapper in a direction toward the mouth of the bag, the free end of the flapper is caused to vibrate up and down causing the free end of the curved leaf spring 65 to be moved up and down into and out of engagement with the exposed edge of the mouth. The curved shape of the leaf spring 65 is such that the coiled end of the spring is also caused to move or extend itself a short distance longitudinally of the bag when it is pressed down against the exposed edge of the mouth so that the frictional contact of the coiled end moved longitudinally a short distance will break the contact between the upper and lower walls in an amount sufficient to permit air to enter the mouth of the bag to effect expansion thereof.

As illustrated in FIGS. 8 and 11, a stream of air is directed toward the mouth of the bag by a blower 74 whose delivery end is secured to an end wall 76 of an air chamber 78. The end wall 76 is secured to the underside of the supporting plate 68 which also serves as the upper wall of the chamber. The chamber is further defined by spaced side walls 80, and a valve plate 82 is pivotally mounted intermediate its ends on a pin 84 extended between and secured to the spaced end walls. The valve plate 82 is arranged to be rocked on its pivot from a position in which the front of the chamber is open, and the back thereof is closed as shown in FIG. 8, to a position as shown in FIG. 11, wherein the back is open and the front closed. The valve plate 82 is rocked to the position shown in FIG. 8 to open the front of the chamber by a roller 86 carried by an arm 88 fast on a rocker shaft 90 and which cooperates with a cam piece 92 secured to the underside of the valve plate 82. At this time the forward end of the plate 82 rests against the hooked member 28, and the rearwardly extended portion of the plate engages the inner face of the end wall 76 as shown. In operation, when the roller arm 88 is rocked to an upright position, as shown in FIG. 11, the valve plate will rock in a clockwise direction by gravity and by the force of the air to present the forward end of the plate 82 in engagement with the front edge of the supporting plate 68 to cut off the air through the front of the chamber, and the rearwardly extended portion of the plate 82 will fall away from the end wall 76 to provide a passageway for escape of the air from the blower 74. It will be understood that the blower is in continuous operation when the machine is running.

While the bag is held in its expanded or inflated condition, as shown in FIG. 8, provision is made for rocking a pair of opposed mouth spreading and article guiding arms 94, 96 into the open mouth. During the bag opening operation the opposed spreader arms 94, 96 are in their contracted position, as shown in FIG. 2 and in broken lines in FIG. 14, and when so disposed the front edge of the upper wall 20 of the bag when expanded

will be lifted above the forward ends of the contracted spreader arms so that the mouth of the bag surrounds said forward ends as shown in FIG. 8. Thereupon, the spreader arms are rocked outwardly to their full line positions shown in FIG. 14 to spread the mouth portion and to form a guide for the article to be inserted into the bag.

As herein illustrated, the opposed spreader arms 94, 96 comprise elongated tapering guides substantially of inverted L-shaped cross section, the open ends of the arms facing each other so as to form a guide for the article to be inserted. The tapering arms are secured at their wider or flared ends to slotted arms 98 arranged substantially at right angles to the spreader arms, the slotted arms being adjustably secured by bolts 100 to the upper ends of pivot studs 102. The pivot studs 102 are supported for rotation in spaced brackets 104 secured to the underside of the supporting plate 68. As shown in FIG. 15, the lower ends of the pivot studs 102 are provided with bevel gears 106 which mesh with bevel gears 108, the latter being fast on the rocker shaft 90.

Provision is made for rocking the shaft 90 to effect spreading of the arms 94, 96 within the bag and to simultaneously rock the valve plate 82 to close the forward end of the air chamber. As herein shown, the shaft 90 is provided with a slotted arm 110 fast thereon which is connected by a link 112 to one arm of a bell crank 114 pivotally mounted on a shaft 116 supported in the machine frame. The second arm of the bell crank is provided with a roller 118 which cooperates with a cam 120 fast on a cam shaft 122. The cam shaft 122 is arranged to be rotated through driving means including an electric motor 124 connected by a belt 126 through a variable drive unit 128 to a speed reducing unit 130. The output shaft of the speed reducing unit is provided with a bevel gear 132 which is in mesh with a bevel gear 134 fast on a continuously rotated drive shaft 136 journaled in the machine frame.

Also mounted on the drive shaft 136 is a conventional magnetic clutch unit, indicated generally at 138, see FIG. 3, and which has associated therewith a spur gear 140 which is free on the shaft 136 when the clutch is deenergized and is caused to rotate with the shaft when the clutch is energized. The spur gear 140 is in mesh with a large gear 142 fast on the cam shaft 122, and another spur gear 144 also in mesh with the large gear 142 is mounted for rotation on a shaft 146 supported in the machine frame. The gear 144 is associated with a magnetic brake unit, indicated generally at 148, arranged to hold the gear 144 stationary when the brake is energized. Both the magnetic clutch unit and the magnetic brake unit form part of an electrical control circuit wherein when the clutch unit is energized the brake unit is deenergized and, conversely, when the clutch unit is deenergized the brake unit is energized.

The control circuit includes means for detecting the presence of an article placed at the intake end of the machine in a position to be advanced during one cycle of operation into operative position to be inserted into a bag during the succeeding cycle of operation. As shown in FIG. 2, the detecting means may comprise a conventional photocell unit 150 disposed at one side of the intake end of the machine, and a cooperating light source unit 151 disposed at the opposite side thereof and arranged so that an article placed at the intake end of the machine will cut off the light source and actuate the photocell. In operation the clutch is energized and the brake is deenergized when an article is placed at the intake end of the machine in the path of the light source to initiate a cycle of operation of the cam shaft 122. The circuit further includes a crank operated, one-revolution limit switch 152, see FIG. 3, arranged to deenergize the magnetic clutch unit 138 and energize the magnetic brake unit 148 to bring the cam shaft 122 to rest at the end of one revolution unless a succeeding article is placed at the in-

take end of the machine in the path of the light source. Thus, in operation the machine will operate continuously through successive cycles as long as successive articles are placed at the intake end of the machine in a position to be detected by the photocell unit.

As illustrated in FIGS. 2 and 4, the intake end of the machine includes a supporting table or platen 154 and a pair of opposed, laterally adjustable hollow guide members 156, 158 mounted thereon providing a path through which the articles are guided into the machine. As shown in FIG. 2, an article 160, herein shown as comprising a group of bakery rolls, is disposed in position A in front of a longitudinally movable inserting member, indicated generally at 162, ready to be advanced from position A and inserted into the open bag when a cycle of operation is initiated. Now, when a succeeding article, shown in position B, is placed in the intake path to intercept the light source of the detecting means and initiate a cycle of operation, the inserting member is moved longitudinally to engage and insert article A into the open bag, and during the same cycle provision is made for advancing the article in position B to position A to be inserted into a bag during a succeeding cycle of operation.

The means for advancing the article from position B to position A includes a pivotally mounted and longitudinally movable pusher member indicated generally at 164 in FIGS. 1 and 4. The pusher member is provided with a plurality of spaced fingers 166 arranged to be extended up through longitudinally extended slots 168 formed in the platen 154 to engage the rear of the article in position B and to move longitudinally in the slots to advance the article to position A. As shown in detail in FIGS. 6 and 7, the fingers 166 are secured at their lower ends in a transverse bar 170 attached to a tie bar 171 extended between spaced arms 172 fast on a rocker shaft 174. The rocker shaft 174 is journaled in a laterally extended portion of a bracket 176 carried by a longitudinally reciprocal unit, indicated generally at 178, which is mounted to slide on longitudinally extended upper and lower rods 180 supported at their ends in spaced upright members 181, 183 attached to the machine frame, see FIG. 1. One end of the rocker shaft 174 is provided with an arm 187 fast thereon which carries a roller 182 for cooperation with a stationary cam 184 secured to an elongated plate 189 supported from the machine frame. In operation when the reciprocal unit 178 is in its retracted position, as shown in FIG. 1, the pivotally mounted pusher member 164 is in its downwardly rocked position with the cam roller 182 resting on a lower guide rail 186 and immediately in front of a pivotally mounted curved end piece 185 of the stationary cam 184. When the reciprocal unit is moved forwardly the roller rides up over the end piece 185 onto the upper surface of the cam 184 to rock the pusher fingers up through the slots to the position shown in FIG. 6. When the reciprocal unit 178 reaches the end of its forward stroke the cam roller 182 rides off the forward end of the upper surface of the cam 184 and falls by gravity onto the lower guide rail 186 to cause the pusher unit to be rocked downwardly preparatory to being returned to its initial position. During the return stroke the cam roller 182 follows the guide rail 186, and when it approaches its fully retracted position it will engage an angular rear edge of the pivotally mounted cam piece 185 to rock the same upwardly to permit passage of the roller beyond the cam piece whereupon the latter will rock by gravity to its initial position to be engaged by the roller 182 during the succeeding cycle of operation to again lift the pusher member 164 up during the forward stroke of the reciprocal unit 178. A leaf spring 191 carried by the plate 189 may engage a pin 193 extended from the cam piece 185 to assist in rocking the same downwardly.

As herein illustrated, see FIG. 1, the reciprocal unit 178 is arranged to be driven through connections from a closed cam 190 fast on the cam shaft 122. A cam lever

192, pivotally mounted at 194 in the machine frame, carries a roller 196 for cooperation with the cam, and the outer end of the cam lever is connected by a link 198 to a lever 200 pivotally mounted at 202. The lever 202 is connected by a link 204 to a carriage 206 forming part of a motion multiplying mechanism, as shown in FIGS. 6 and 7. The carriage is provided with a gear 208 supported for rotation therein and which is in mesh at its lower edge with a stationary rack 210 secured to the machine frame. The upper edge of the gear 208 is in mesh with a second rack 212 which is secured by bolts 214 to the reciprocable slide unit 178. As shown in FIG. 7, the slide unit 178 includes upper and lower slide blocks 216 which slide on the rods 180 and which are connected by an upright plate 218 to which the pusher member bracket 176 is connected by bolts 220. The carriage 206 is guided for longitudinal movement and, as herein shown, the carriage is provided with spaced lower rollers 222 which ride on tracks 224 secured to opposite sides of the stationary lower rack 210. The carriage is also provided with spaced upper rollers 226 which ride on tracks 228 secured to opposed sides of the upper rack 212. With this construction it will be seen that when the carriage 206 is moved forwardly through a predetermined distance with the gear 208 rolling on the stationary rack 210, the upper rack 212 will be moved forward a relatively greater distance than the carriage so as to effect a relatively long travel of the pusher member 164. Also mounted on the laterally extended portion of the bracket 176 of the reciprocable unit 178 is an elongated tray 230 which extends below and beyond the forward end of the platen 154 to provide a movable support for the article during the inserting operation and during transfer of the article and the bag onto the discharge conveyer indicated generally at 232.

From the description thus far it will be seen that during the initial portion of a cycle of operation an article to be packaged is moved from position B to position A and, simultaneously therewith, the article which was in position A is moved forward by the inserting member 162 to insert the article in the open bag so that the intake path is clear to permit movement of a succeeding article into the position previously occupied by the article in position A. During the inserting movement the article will be pushed off the forward end of the platen 154 onto the moving tray 230, the latter being extended into the open bag to support the article as it is pushed between the opposed guide members 94, 96 and into the bag by the inserting member 162. In operation the inserting member 162 is moved forward in a continuous movement from the full line position shown in FIG. 1 to the furthermost broken line position indicated at 234 to transfer the filled bag onto the conveyer 232, the tray 230 also being moved along with but independently of the inserting member to support the article and the bag as it is moved across the void between the inserting station and the conveyer. In practice, when the forward end of the article is fully seated in the bag during the continuous movement of the inserting member with the forward end of the tray inserted within the bag, the flap end 18 of the bag held in the stack by the retaining member 16 is forcibly withdrawn therefrom by such movement of the inserting member. In operation the flap portion 18 is withdrawn from under the horizontal leg of the retaining member and off the vertical legs thereof. As illustrated in detail in FIG. 12, in order to facilitate withdrawal of the flap 18 from the vertical legs of the retaining member, the openings in the flaps are provided with slits 19 extending from the openings to the edge of the flap.

Referring again to FIG. 1, it will be seen that at the end of the forward stroke of the inserting member 162, as indicated at 234 in FIG. 1, the filled bag is deposited on the conveyer 232 with the end of the bag in engagement with an adjustable stop rail 235 supported from one side of the conveyer. Thereafter, during the retracting stroke, the inserting member is withdrawn from the bag and is

then rotated in a clockwise direction as indicated at the broken line position 236. During the continued return movement of the inserting member it continues its clockwise rotation so that when it is returned to its initial position the inserting member will assume its downwardly rotated position in back of the article deposited at position A in readiness for a succeeding inserting operation.

As herein shown, the inserting member, indicated generally at 162, comprises a bent plate having a vertical pusher leg 238 and a rearwardly extended angular leg 239, the ends of both legs being connected to a semicircularly curved rod 240. The upper end of the rod is connected to a collar 242 which is detachably secured to a reduced diameter threaded end of a shaft 244 by a hand nut 246. The shaft 244 is journaled in a bearing 248 secured to a longitudinally reciprocable bracket 250. Provision is made for reciprocating the bracket 250 through cam operated motion operated multiplying mechanism indicated generally at 252 and for controlling the position of the inserting member 162 during reciprocation of the bracket 250 through driving mechanism indicated generally at 254 in a manner such as to maintain the inserting member in a downwardly rotated or inserting position during the forward stroke thereof and to effect withdrawal and clockwise rotation of the inserting member to its initial position during the retracting stroke thereof.

As illustrated in FIGS. 17 and 18, the bracket 250 is supported for longitudinal reciprocation on a stationary grooved rail 256 in which upper and lower rollers 258 are arranged to ride. The grooved rail is supported between and secured to upright end plates 260 attached to the machine frame. The bracket 250 is further supported for reciprocal movement on an elongated rod 262 also supported between the end plates 260 and which extends through a slide bearing 264 to which the lower end of the bracket 250 is secured. The slide bearing 264 is secured by bolts 265 to the upper face of an elongated upper rack 266 which forms a part of the motion multiplying mechanism 252. The rack 266 is in mesh with a gear 268 mounted for rotation in a carriage 270 and which is also in mesh with a lower stationary rack 272 attached to the machine frame. The carriage is also provided with upper and lower rollers 274 arranged to ride on elongated rails 275 secured to the upper and lower racks 266, 272. The carriage is connected by a relatively short link 276 to the upper end of a lever 278 pivotally mounted at 280 in the machine frame as shown in FIG. 1. The lever 278 is connected by a link 282 to a crank arm 284 fast on the cam shaft 122. In operation, when the cam shaft 122 is rotated through one revolution, the carriage will be reciprocated as the gear 268 rolls along in mesh with the lower rack 272, and the upper rack 266, also in mesh with the gear 268, will be reciprocated through a relatively greater distance than the carriage 270 to provide a relatively long movement of the bracket 250 and the inserting member 162 carried thereby. As shown in FIG. 3, the end of the crank arm 284 is arranged to engage and close the switch 152 to bring the cam shaft to rest at the end of one revolution unless a succeeding article is in operative position at the intake end of the machine to be detected by the photocell 150 as above described.

As further illustrated in FIGS. 17 and 18, the shaft 244 to which the inserting member is secured is provided with a sprocket 286 connected by a chain 288 to a sprocket 290 loosely mounted on a shaft 292 journaled in the bracket 250. A chain tightener sprocket 291 carried by a pivotally mounted arm 293 is urged in tightening engagement with the chain by a spring 295. The shaft 292 is also provided with a gear 294 fast thereon which is in mesh with a vertical rack 296 movable in guides 298 secured to the bracket 250. The lower end of the rack 296 is provided with a cam roll 300 arranged to cooperate with a stationary cam track 302 to effect vertical reciprocation of the rack when the bracket 250 is reciprocated longitudinally.

The cam track 302 is formed in an elongated plate 304 secured at its ends to the upright end plates 260.

The driving mechanism 254 for controlling the position of the inserting member 162 includes mechanism for holding the loose sprocket 290 stationary on the shaft 292 during the forward or inserting stroke, at which time the rack 296 is being moved upwardly to effect counterclockwise rotation of the shaft 292, and during the retracting stroke the rack is being moved downwardly to cause the sprocket 290 to be rotated in a clockwise direction to return the inserting member to its initial position.

As herein shown, the loosely mounted sprocket 290 is provided with a one-tooth ratchet 306 formed integrally therewith, and the gear 294, fast on the shaft 292 is provided with a pawl disk 308 which carries a spring pressed pawl 310. During rotation of the gear and the pawl in a counterclockwise direction the pawl will slide on the ratchet, and during rotation of the gear and the pawl in a clockwise direction the pawl will engage in the tooth of the ratchet to effect rotation thereof. In order to maintain the inserting member 162 in its downwardly rotated inserting position during the forward stroke, counterclockwise rotation thereof is prevented by the extended end of a pin 312 carried by the sprocket and which is arranged to engage the curved end of a retaining arm 314 pivotally mounted at 316. A second arm 318 of the retaining member is connected by a spring 319 to a stud 320 secured to a tie bar 322 carried by the bracket 250. The arm 318 is also provided with an adjustable stop screw 324 arranged to engage the bar 322 to limit the movement of the retaining arm 314. In operation, when the shaft 292 is rotated in a counterclockwise direction, the pin 312 will engage the curved end of the arm 314 to prevent rotation of the loosely mounted sprocket 290 in a counterclockwise direction whereby to maintain the inserting member 162 in its operative inserting position during the forward stroke as shown in FIG. 17. Since the inserting member is underload during the forward stroke there is no tendency for the same to rotate in a clockwise direction during this time. Also, during the forward stroke the cam roll 300 is traveling upwardly in its track 302, and when the inserting member starts its retracting movement the roll 300 will ride along a horizontal portion 303 of the track until the inserting member is withdrawn from the open end of the bag whereupon the roll 300 starts its downward movement in the track to effect clockwise rotation of the gear 294. The spring pressed pawl 310 will now engage the tooth of the ratchet 306 to effect clockwise rotation of the inserting member 162, the pin 312 being rotated away from the arm 314 at this time. During the retracting stroke the inserting member continues its clockwise rotation, and as it approaches the end of the stroke the pin 312 will engage the lower edge of the spring urged retaining arm 314, as shown in FIG. 19, in order to counteract the flywheel effect of the inserting member. During continued positive rotation of the sprocket 290 in a clockwise direction the pin 312 will lift the arm 314 and pass beyond the curved end thereof whereupon the spring urged arm 314 will return to its downwardly rocked retaining position. At this time the vertical rack 296 has reached the end of its downward stroke, and a right angle stop member 326 secured to the upper end of the rack is moved into the path of the opposite extended end of the pin 312 carried by the sprocket 290 whereby to provide a positive stop to lock the inserting member in its downwardly rocked vertical position at the end of the retracting stroke as shown in FIG. 17. In order to prevent damage to the parts in the event that an undue strain is inadvertently placed on the inserting member 162, provision is made for separably connecting or releasably securing the sprocket 286 to the inserter shaft 244. As shown in FIGS. 15 and 16, the sprocket 286 may be loose on the shaft, and the outer end of the shaft is provided with a flange member 400 fast thereon. The flange member is provided with a V-notch 402 in its periphery for cooperation with a

V-shaped lug 404 carried by a ring 406. The ring is pivotally mounted at 408 to a disk 410 secured to the sprocket 286. A coil spring 412 connected at one end to the disk 410 and at its other end to the ring 406 serves to retain the lug 404 in driving engagement with the notch 402. In operation, in the event that the inserting member is subjected to an undue strain, such as to effect rotation of the shaft 244 relative to the sprocket 286, the lug 404 will ride out of the notch 402, and the ring 406 will be rocked on its pivot to the dotted line position shown in FIG. 16 to release the connection. A bolt 414 extended loosely through a slot 416 in the ring 406 and secured to the disk 410 is provided to limit rocking movement of the ring.

From the description thus far it will be seen that during the continuous forward stroke the inserting member 162 inserts the article into the bag and transfers the filled bag to the conveyor indicated generally at 232. As herein shown, the conveyor 232 is arranged at right angles to the direction of movement of the inserting member 162 and includes a plurality of spaced endless belts 328 arranged to run over end pulleys 330, 332 journaled in side plates 334, 336 supported from the machine frame and connected by transverse tie bars 338. The belts 328 are maintained in their spaced relation by collars 333 secured to the end pulley 332. Each belt passes around a drive pulley 340 mounted for rotation on a shaft 342 carried between depending plates 344 secured at their upper ends to the side plates 334, 336. Vertically adjustable and flanged belt tightener pulleys 337 are also arranged to engage the individual belts, as shown in FIG. 5, to urge the belts into driving engagement with the drive pulley 340 and to maintain spaced alignment of the belts. A cover plate 341, over which the belts run, may extend between the upper edges of the spaced side plates 334, 336.

The belts 328 are arranged to be continuously driven and, as herein shown, a sprocket 346 secured to one end of the pulley 340 is connected by a chain 348 to a sprocket 350 fast on one end of an elongated drive shaft 352 journaled in bearings 354 depending from the machine frame as shown in FIG. 1. The other end of the shaft 352 is provided with a spur gear 356 which meshes with a similar gear 358 fast on the opposite end of the output shaft of the speed reducing unit 130.

Since the conveyor belts 328 are continuously driven provision is made for supporting the filled bag above the conveyor, and thereafter when the inserting member is withdrawn provision is made for lowering the delivered bag onto the moving belts to be discharged from the machine.

As herein shown, the bag supporting mechanism includes a plurality of elongated rollers 360 which are supported to be extended upwardly between the spaced belts 328 and through slots provided in the cover plate 341. The rollers 360 are supported for rotation on pins 362 carried by upwardly extended portions 364 of spaced brackets 366 connected together by tie rods 368 as shown in FIGS. 11 and 20. The brackets 366 are connected to the upper ends of parallel links 370 which are fast on spaced shafts 372 mounted to rock in the side plates 334, 336. The parallel linkage is arranged to be rocked through cam operated connections and, as herein shown, one of the parallel links 370 is provided with an extension 374 connected by a link 376 to an arm 378 mounted to rock the shaft 116. A second arm 380 formed integrally with the arm 378 carries a cam roller 382 arranged to cooperate with a cam 384 fast on the cam shaft 122. In operation the supporting rollers 360 are disposed in their elevated position above the belts to receive the filled bag transferred thereto, and after the inserting member is withdrawn the supporting rollers are rocked downwardly below the belts to permit the filled bag to rest on the continuously moving belts to discharge the bag from the machine.

The filled bag, which is considerably longer than the article contained therein, is subsequently de-

livered to a trimming and sealing machine, which forms no part of the present invention, and wherein the extended mouth portion of the bag is trimmed and heat sealed to complete the packaging operation.

Provision is made in the illustrated embodiment of the invention for discontinuing operation of the machine when the stack of bags is depleted from the magazine. As shown in FIG. 8, a contact member 386 carried by a bar 388 attached to the underside of the air chamber side plates 80, and extended to one side of the stack, is arranged in the path of a portion of the elevating platform 12. In operation, as successive bags are withdrawn from the stack and the platform 12 is elevated, the platform will eventually engage the contact member 386. The contact member may form part of a circuit to operate a relay to discontinue operation of the machine.

Provision is also made for detecting the presence of a bag about the article during transfer to the conveyor 232. During normal operation the supporting tray 230 extends into the open bag and moves along with the bag until it reaches a point immediately adjacent the side of the conveyer 232. At this time the end of the supporting tray will strike a contact 390 supported from the side of the conveyer in the path of the tray. The presence of a non-conducting plastic bag covering the end of a tray serves to insulate the tray from the contact. However, in the event that a bag fails to be opened and is not in position to receive a bag the article will be transferred onto the conveyer without a bag. At such time engagement of the bare end of the tray 230 with the contact 390 will likewise operate a relay to discontinue operation of the machine.

From the above description it will be seen that in the operation of the illustrated packaging machine, when an article is placed at the intake end of the machine in the path of the photocell detector, a cycle of operation is initiated to start the inserting member 162 on its forward stroke to insert an article into an open bag and to start the pusher member 164 to move the newly placed article into position to be inserted into a succeeding bag. It will be understood that the front of the air chamber has been previously opened at the time when the spreader arms 94, 96 were rocked inwardly during the retracting stroke of the inserting member so that an open bag is already in position to receive the article being advanced. Prior to arrival of the article at the inserting station the spreader arms 94, 96 are rocked outwardly into the open mouth of the bag to spread the mouth and to form a guide for the articles. The supporting tray 230, which is moved forward into the open bag, supports the article at this time, and during continuous movement of the inserting member 162 and the tray 230 the article is fully seated in the bag, and the filled bag is fully withdrawn from the stack and from the spreader arms to be transferred onto the supporting rolls 360 disposed above the conveyer belts 328. Thereafter, the tray and pusher are retracted; the inserting member is retracted; the spreader arms are rocked inwardly; and the supporting rollers are lowered below the conveyer belts to deposit an article on the moving belts to be carried away from the machine.

In the embodiment of the invention above described the article advancing mechanism 164 and the article supporting tray 230 are carried by the same bracket 176 and operate simultaneously through the motion multiplying mechanism 206 as shown in FIG. 6. In a modified embodiment of the invention, as illustrated in FIG. 21, the article supporting tray may be operated by the mechanism 206, as before, but the article advancing mechanism is arranged to be operated independently of the motion multiplying mechanism. As herein shown, the article advancing member, indicated at 420 in FIG. 21, comprises a plurality of spaced pusher fingers 422 carried by a transverse shaft 424 supported at the forward end of a longitudinally reciprocable carriage 428. The carriage is provided with rollers 430 arranged to ride in

tracks formed in side guide rails 432. One end of the shaft 424 is provided with an arm 434 fast thereon and which is provided with a roll 436 for cooperation with a stationary cam rail 438. The arm 434 is also connected by a link 440 to the upper end of a two-armed lever 442 pivotally mounted at 444 in a bracket 446 secured to and depending from the carriage 428. The second arm of the lever 442 is connected by a link 448 to the cam operated arm 200. The depending bracket 446 is also provided with opposed set screws 450, 452 arranged to cooperate with the lever 442. In operation, when the carriage 428 is in its retracted position, as illustrated, the lever 442 is rocked to the left against the stop screw 450, and the pusher fingers 422 are in their downwardly rocked or inoperative position. Now, when the cam operated arm 200 is rocked to the left to start the forward stroke, the lever 442 is first rocked to the right against the set screw 452 which rocks the pusher fingers 422 upwardly, as shown in broken lines, and upon continued movement of the cam operated arm 200 the carriage and the pusher fingers mounted thereon are advanced to move the article into operative position to be engaged by the inserting member during a succeeding cycle of operation. It will be observed that the roll 436 will ride along the cam rail 438 during the forward stroke to maintain the fingers in their upwardly rocked position, and when the roll leaves the forward end of the cam rail at the end of the forward stroke the linkage is free to be reversed at the beginning of the retracting stroke to present the lever 442 against the set screw 450 to rock the pusher fingers downwardly. Upon continued retracting movement the carriage and the pusher fingers will be returned to their initial position, engagement of the roll 436 with the rail 438 maintaining the fingers in their downwardly rocked position until the roll leaves the rear portion of the rail where the linkage is free to be again rocked during the beginning of the forward stroke as described.

Referring now to FIG. 22, in a further modified form of the present invention novel provision is made for mechanically separating the walls at the mouth of the uppermost bag in the stack to permit air to enter and expand the bag. Provision is also made for supporting the bags in a novel manner such as to maintain the uppermost bags in a substantially horizontal plane as the stack becomes depleted whereby to facilitate opening of successive bags.

As herein shown, the mechanism for mechanically separating the walls at the mouth of the uppermost bag includes a pair of spaced serrated elements or thumbs 500 arranged to be moved forwardly and downwardly into frictional engagement with the marginal portion of the upper wall of the bag to positively break the contact between the upper and lower walls whereby to permit the air to enter and expand the bag. Each serrated thumb 500 is secured to a pivotal arm 502 carried by longitudinally reciprocable slide bars 504. The slide bars 504 are mounted to slide on grooved rails 506 secured to the side walls 80 of the air chamber 78, the upper edges of the slide bars being confined by the plate 68 defining the upper wall of the chamber. The arms 502 are pivoted at 503 and are also provided with rollers 508 arranged to ride in cam slots formed in opposed stationary cam blocks 510 secured to the underside of the plate 68. Springs 512 secured to extensions of the arms 502 are connected at their other ends to the slide bars 504 and tend to urge the serrated thumbs downwardly when permitted to do so by the cam blocks 510.

In order to reciprocate the slide bars 504 and the serrated thumbs carried thereby, the bars are provided with gear racks 514 adjustably secured thereto and which are arranged to cooperate with gear segments 516 keyed to a shaft 518 journaled in bearing brackets 520 attached to the walls of the air chamber. An arm 522 fast on the shaft 518 is connected by a link 524 to one arm 526 of a bell crank pivotally mounted on a stud 528 supported in brackets 530 attached to the frame of the machine. The second arm 532 of the bell crank carries a roller 534

for cooperation with a cam 536 fast on the cam shaft 122. A spring 538 connected to the arm 526 and to a spring stud 540 attached to the frame tends to hold the roller 534 against its cam.

In operation the pivotally mounted and longitudinally reciprocable thumbs 500 are upwardly rocked when they are in their retracted position, as shown in FIG. 22, being held in such position by the cam paths in the blocks 510, and when the thumbs are moved forwardly out of the rear portion of the cam paths they are rocked downwardly by the springs 512 to frictionally engage the marginal portion of the upper wall of the bag whereby to break the adherence of the upper wall to the lower wall of the bag as shown in FIG. 23. The thumbs 500 are then retracted and returned to their initial upwardly rocked position prior to releasing the air to enter between the opened walls of the bag. The front of the air chamber 78 is opened after the thumbs have been retracted and during the inward or closing movement of the pivotal bag spreading and article guiding arms 94, 96 of a previous cycle of operation. The air thus released from the air chamber effects opening of the uppermost bag in readiness to receive an article during a succeeding cycle, and when the bag spreading arms are rocked outwardly to spread the bag open, the front of the air chamber is again closed. It will be observed that a curved guide member 542 extends forwardly and downwardly in front of the air chamber 78 to direct the air from the chamber downwardly in front of the exposed edge of the upper wall of the bag.

The modified form of stack supporting and elevating unit, also shown in FIG. 22, is indicated generally at 544 and is particularly designed for handling flat plastic bags, such as thin sheet polyethylene bags, which have a two-ply portion comprising the upper and lower walls of the bag, a single-ply portion at the mouth which comprises the extended flap, and a four-ply portion at the bottom or closed end of the bag which comprises a gusseted portion. Such bags when stacked in their flat condition on a flat platform will naturally assume an uneven or angular position at the top of the stack, the rear of the stack being greater in height at the four-ply portion, and the front of the stack being less in height at the single-ply flap portion.

The modified stack supporting and elevating unit 544 is arranged to maintain the top or uppermost portion of the stack in a substantially horizontal or level position in order to facilitate the opening operation. Provision is also made for providing a hump at that portion of the stack adjacent the exposed edge of the upper wall of the bag against which the longitudinally reciprocable thumbs 500 engage to break the adherence of the upper and lower walls as described.

As herein illustrated, the modified stack supporting and elevating unit comprises an elevating support including a pair of elongated spaced rails 546 which extend through slotted portions in a supporting plate 548 attached to the machine frame. The spaced rails are connected by upper and lower tie pieces 550, 552 disposed in front of and in back of the plate 548 and which carry rollers 554, 556 arranged to ride on opposite edges of vertical guide bars 558, 560 secured to the edges of the supporting plate 548 as shown in FIGS. 22 and 24. Elongated coil springs 562 are connected between studs 564 extended from the spaced rails 546 and studs 566 extended from the machine frame and which serve to urge the elevating support upwardly. In order to maintain the elevating support in its down position when not in use or when loading the magazine with a new stack of bags, an elongated spring pressed rod 568 is provided for engagement with the underside of a bar 570 secured to the vertical supporting plate 548. The spring pressed rod 568 may be supported for sliding movement in suitable bearings 571 secured to one of the spaced rails 546 and is provided with a handle 572 as shown.

The elongated rails 546 are arranged to detachably and slidably support a lower plate 574 mounted on spaced bars 576 provided with conventional slide units indicated

generally at 578 for sliding engagement with the rails 546. A bag supporting platform 580 is carried by and arranged to move vertically relative to the lower plate 574 for a purpose which will hereinafter appear. The size of the platform 580 is such as to support the two-ply portions of the stack while the four-ply end portions of the stack extend beyond the end of the platform to permit them to fan out in a downward direction and in a manner such as to maintain the bags in the uppermost portion of the stack in a substantially horizontal position as shown in FIG. 23. The lower plate 574 is provided with an upstanding member 582 against which the single-ply portions of the stack rest. A U-shaped retaining member or wicket 584 extends through openings in the single-ply flap portions of the bags, the legs of the wicket being slidably supported in insulated openings formed in the member 582. A wicket stop 586 supported in front of and below the mouth of the air chamber is provided with a grooved portion 588 for receiving the horizontal leg of the wicket, the lower face of the stop 586 bearing against the upper surface of the single-ply portion of the stack to serve as a limiting stop for the upwardly urged stack so as to maintain the mouth portion of successive uppermost bags in the stack in a predetermined position relative to the opening mechanism. A spring pressed bail 589 carried by the limiting stop 586 may project into the grooved portion 588 to detachably retain the horizontal leg of the wicket in the groove. The platform 580 is provided with a projection 590 on the upper face thereof and against which the bags rest to provide a hump 591 in the upper portion of the stack immediately beyond the exposed edge of the upper wall of the bag for cooperation with the longitudinally and pivotally movable thumbs 500 to break the adherence between the upper and lower walls of the bag preparatory to opening the bag. The stop 586 may be mounted on a central pin 592 to permit slight rocking thereof to conform to any slight deviation from a horizontal plane of the top of the single-ply portion of the stack.

From the description thus far it will be seen that when the platform 580 is in its lowermost position relative to the lower plate 574 for supporting a full stack the distance from the platform supporting the double-ply portions of the bags to the upper surface of the upstanding member 582 supporting the single-ply portions of the bags is such as to maintain the upper portion of the stack in a substantially horizontal plane. However, in operation, as successive bags are withdrawn and the stack is lowered, the double-ply portion will be lowered twice as fast as the single-ply portion of the stack so that eventually the double-ply portion of the stack would be lowered to an extent such as to be out of contact with the thumbs 500. In order to avoid this occurrence provision is made for elevating the platform 580 relative to the lower plate 574 and the member 582 carried thereby in a manner such as to compensate for the depletion of the stack by continued withdrawals therefrom whereby to maintain the upper portion of the stack in a substantially horizontal plane. As herein shown, the platform is supported by two spaced depending brackets 594 which are pivotally connected at their lower ends to one arm of a bell crank 596.

The bell crank is pivotally mounted on a pin 598 carried by a bracket 600 depending from the underside of the lower plate 574, and the second arm of the bell crank is provided with a roller 602 for cooperation with a stationary cam piece 604 adjustably supported in a bracket 606 attached to the frame of the machine. The brackets 594 are guided by a pin 608 secured to the spaced bars 576 and which extends through curved slots 610 formed in the brackets. The slots 610 are arranged to compensate for the rocking movement of the bell crank so as to maintain the platform in a horizontal position as it is elevated relative to the lower plate 574. A coil spring 612 is connected between the bell crank 596 and the pin 608 to hold the roller 602 against its cam piece 604. With this construction it will be seen that in operation when the

magazine is provided with a full stack, as shown in FIG. 23, the platform 580 supporting the double-ply portions of the stack is in a lowered position relative to the upper end of the single-ply supporting member 582. Thereafter, as the bags become depleted, and the bag supporting mechanism is bodily moved upwardly as a unit, the roller 602 will follow the angular surface 603 of the cam piece 604 to effect elevation of the platform 580 relative to the member 582 in an amount substantially proportionate to the reduced thickness of the double-ply portion of the stack so as to maintain the top of the stack in a substantially horizontal plane. Thus, as shown in FIG. 22, wherein only a few bags are left in the stack, the platform 580 is shown in its extreme upward position in a plane slightly higher than the top of the single-ply supporting member 582 to maintain the top of the depleted stack in a position for cooperation with the thumbs 500 to open the bag. The elongated coil springs 562 are designed so that the full stack is urged upwardly against the stop member 586 with a predetermined force, and as the bags are depleted and the weight of the stack is reduced, the tension of the springs is such as to continue to maintain such predetermined upward force as the bags are depleted.

In practice the relatively thin sheet polyethylene bags tend to curl up along their longitudinal marginal edges which may cause some difficulty in opening the bags. In order to cause these edges to lie flat for most efficient opening operation the width of the supporting platform 580 may be reduced less than the width of the bags so as to permit the edges of the bags to hang over the sides of the platform in a manner similar to the expedient used to take care of the four-ply edges of the bags which hang over the end of the platform. In addition, in order to assure that the marginal edges of the bags assume a flat position, a pair of spaced hold-down clips 614 are provided, see FIG. 25, which are supported from the plate 68 and which are arranged to engage the tops of the marginal edges of the stack adjacent the mouth portions of the bags as the stack is elevated into operative position to the opening mechanism.

As previously described, provision is also made in the control circuit of the modified embodiment of the machine for discontinuing operation thereof when the stack of bags is depleted. The bags provide insulation between the contacting surfaces of the stop member 586 and the member 582, and when the last bag of the stack is removed contact will be made to operate a relay, not shown, to discontinue operation. The wicket 584 may be supported in insulating bushings 615 so as to prevent the control from being actuated through the wicket.

Referring now to FIG. 26, a further modified form of the article advancing mechanism is therein shown wherein the pusher fingers 616 are carried by and movable with the forward end of a longitudinally reciprocable carriage 618 similar to the carriage shown in FIG. 21 and wherein the carriage is provided with a depending bracket 620 connected by a link 622 to the crank operated arm 278. The arm 278, as previously described, is connected by a link 276 to the motion multiplying gear carriage 252 which operates the inserting mechanism 162 as before. Thus, in operation, the article advancing mechanism operates simultaneously with the inserting mechanism but travels only one half the distance of the inserter since it is not linked to the motion multiplying carriage. In this embodiment the tray 230 is operated independently by the cam operated arm 200 and motion multiplying gear carriage 206.

The fingers 616 are fast on a rocker shaft 624 journaled in suitable bearings mounted on the reciprocable carriage 618. One end of the shaft 624 is provided with an arm 626 fast thereon having a roller 628 which is arranged to ride along the undersurface of a guide track 630. When the carriage is in its retracted position, as shown in full lines in FIG. 26, the pusher fingers 616 are in their rearwardly rocked or horizontal position and are maintained

in such position by a pivotally mounted locking element 632 having a semicylindrical portion 634 at its free end arranged to engage in a notch formed in a collar 638 also fast on the shaft 624. The other end of the locking element 632 is provided with a semicircular groove which fits over a semicylindrical projection 640 formed in the underside of an extended portion of a bracket 642 mounted on the carriage 618. An elongated coil spring 644 connects the locking elements 632 to the bracket 620 to hold the pusher fingers in their locked position.

The cam roller 628 also cooperates with a cam piece 646 pivotally mounted on a stud 648 carried by an arm 650 secured to the machine frame. The cam piece 646 is urged to rock in a clockwise direction by a coil spring 652 connected between the cam piece and the machine frame. The cam piece is limited in its upward or clockwise movement by a stop pin 654 carried by the cam piece which engages the underside of the arm 650 but is free to yield downwardly. In operation, when the carriage 618 is moved forwardly or to the left viewing FIG. 26, the roller 628 is urged in a counterclockwise direction by engagement with the angular cam surface 666, and as a result the shaft 624 is rocked to move the portion 634 of the resiliently held locking element 632 from its notch. During continued forward movement the pusher fingers 616 are rocked to a vertical position and are arranged to be locked in such position by engagement of the portion 634 with a second notch spaced about ninety degrees from the first notch. At this time the arm 626 and its roller 628 has rotated through about ninety degrees with the roller 628 coming to rest against the underside of the track 630. When in this position the roller 628 urges the cam piece downwardly to permit the roller to pass beyond the cam piece, the latter then returning to its initial position by virtue of the spring 652.

It will be understood that in operation an article to be inserted into a bag is placed in front of the reciprocable carriage 618 and the pusher fingers 616 carried thereby, and that the article is advanced thereby from position B to position A, as shown in FIG. 2, in timed relation to the movement of the inserting member 162 which engages the advanced article during the following cycle of operation to insert the article into a bag. As illustrated in FIG. 22, pivotally mounted and weighted top guides 665 may be provided to engage the tops of the articles during their movement immediately prior to entering the article guiding and bag spreading arms 94, 96 to prevent upward displacement thereof during such movement. As also shown in FIG. 26, when the article advancing carriage 618 and the pusher fingers 616 carried thereby approach the end of its forward stroke, provision is made for again rocking the pusher fingers rearwardly to a horizontal position. This is accomplished by an adjustable stop screw 668 carried by a bracket 670 secured to the machine frame. The stop screw is arranged to engage an extension 672 of the arm 626, as shown in broken lines at the left of FIG. 26, and during continued forward movement to the end of the stroke, the shaft 624 is rocked in a clockwise direction to remove the resiliently held portion 634 from the second notch of the collar 638 which will then again engage the first notch to maintain the fingers in their horizontal position during their return stroke. Thereafter, when the advancing carriage 618 approaches the end of its return stroke, the roller 628 riding along the track 630 will engage a second angular surface 674 of the cam piece 646 which causes the cam piece to yield and permit passage of the roller beyond the angular surface 674 to come to rest in engagement with the angular surface 666 at the end of its retracting stroke in readiness for a succeeding cycle of operation.

While the preferred embodiment of the invention has been herein illustrated and described, it will be understood that the invention may be embodied in other forms within the scope of the following claims.

Having thus described the invention, what is claimed is:

1. In a packaging machine, in combination, means for supporting a stack of flat envelope type bags, each having an upper wall and a lower wall, one wall being provided with an extended flap portion, means cooperating with said extended flap portions for retaining the stack on said supporting means leaving the edge of said upper wall free and exposed, means for directing a stream of air against said exposed edge, and a longitudinally reciprocable mechanically operated element frictionally engageable with the marginal portion of said exposed edge for breaking the adherence of the upper wall to the lower wall to permit the air to enter therebetween to expand the bag in readiness to receive an article to be packaged.

2. In a packaging machine, in combination, means for supporting a stack of flat envelope type bags, each having an upper wall and a lower wall, one wall being provided with an extended flap portion, means cooperating with said extended flap portions for retaining the stack on said supporting means leaving the edge of said upper wall free and exposed, means for directing a stream of air against said exposed edge, and a pair of longitudinally reciprocable serrated elements frictionally engageable with the marginal portion of said exposed edge for breaking the adherence of the upper wall to the lower wall to permit the air to enter therebetween to expand the bag in readiness to receive an article to be packaged, said longitudinally reciprocable serrated elements being pivotally mounted and resiliently rocked into frictional engagement with said marginal portion of the exposed edge.

3. In a packaging machine, in combination, means for supporting a stack of flat envelope type bags, each having an upper wall and a lower wall, one wall being provided with an extended flap portion, means cooperating with said extended flap portions for retaining the stack on said supporting means leaving the edge of said upper wall free and exposed, means for directing a stream of air against said exposed edge, and a pair of longitudinally reciprocable serrated elements frictionally engageable with the marginal portion of said exposed edge for breaking the adherence of the upper wall to the lower wall to permit the air to enter therebetween to expand the bag in readiness to receive an article to be packaged, said longitudinally reciprocable serrated elements being also pivotally mounted and resiliently rocked downwardly into frictional engagement with the marginal portion of said exposed edge during their forward stroke, and stationary cams cooperating with rollers carried by said reciprocable elements for rocking the elements upwardly during their return stroke.

4. In a packaging machine, in combination, means for supporting a stack of flat envelope type bags, each having an upper wall and a lower wall, one wall being provided with an extended flap portion, means cooperating with said extended flap portions for retaining the stack on said supporting means leaving the edge of said upper wall free and exposed, means for directing a stream of air against said exposed edge, and a pair of spaced longitudinally reciprocable serrated elements mounted to rock into and out of frictional engagement with the marginal portion of said exposed edge to break the adherence of the upper wall to the lower wall to permit the air to enter therebetween to expand the bag in readiness to receive an article to be packaged, and means for longitudinally reciprocating said serrated elements.

5. The combination defined in claim 4 wherein the means for reciprocating said elements includes a pair of slidably mounted gear racks and a pair of cam operated segmental gears cooperating with said racks.

6. In a packaging machine, in combination, means for supporting a stack of flat envelope type bags, each having an upper wall and a lower wall, one wall being provided with an extended flap portion, means cooperating with said extended flap portions for retaining the stack on said supporting means leaving the edge of said upper wall free and exposed, means for directing a stream of air

against said exposed edge, a longitudinally reciprocable mechanically operated element frictionally engageable with the marginal portion of said exposed edge for breaking the adherence of the upper wall to the lower wall to permit the air to enter therebetween to expand the bag in readiness to receive an article to be packaged, and means for inserting an article into the open bag arranged to effect withdrawal of the flap portion from said retaining means upon continued movement of said inserting means after the article is fully seated in the bag.

7. In a packaging machine, in combination, means for supporting a stack of flat envelope type bags, each having an upper wall and a lower wall, one wall being provided with an extended flap portion, means cooperating with said extended flap portions for retaining the stack on said supporting means leaving the edge of said upper wall free and exposed, means for directing a stream of air against said exposed edge, a longitudinally reciprocable mechanically operated element frictionally engageable with the marginal portion of said exposed edge for breaking the adherence of the upper wall to the lower wall to permit the air to enter therebetween to expand the bag in readiness to receive an article to be packaged, pivotally mounted opposed mouth spreading and article guiding means arranged to be rocked into the mouth of the opened bag, and a longitudinally reciprocable inserting member arranged to insert an article between said guide means and into the bag, continued movement of the inserting member effecting withdrawal of the bag from said guiding means and said retaining means.

8. In a packaging machine, in combination, means for supporting and elevating a stack of flat bags, each bag having an upper wall and a lower wall forming a double-ply portion and an extended flap forming a single-ply portion at the mouth of the bag, means for opening and withdrawing successive uppermost bags from the stack, said bag supporting means including a vertically movable elevating support having an upstanding member for supporting the single-ply flap portion of the stack, stop means engageable with the upper surface of the single-ply portion of the stack for maintaining the mouth portions of successive uppermost bags in a predetermined bag opening position, a platform carried by and movable relative to said vertically movable elevating support for supporting the double-ply portion of the stack, said platform being disposed at a substantially lower level than said single-ply support when a relatively high stack of bags is initially supplied to the platform to arrange the top of the double-ply portion of the stack substantially level with the top of the single-ply portion thereof, and means for automatically raising said platform relative to the elevating support and said single-ply support as the stack is depleted by successive withdrawals therefrom whereby to maintain the top of the double-ply portion of the stack in a plane substantially level with the top of the single-ply portion during such successive withdrawals.

9. The combination as defined in claim 8 wherein each bag is also provided with a four-ply gusseted closed end portion, said platform being of a length less than the length of the bags to permit the four-ply portions to hang over the end of the platform and to fan out downwardly whereby to maintain the top of the four-ply portion of the stack in a plane substantially level with the top of the remaining portions of the stack.

10. The combination as defined in claim 9 wherein the platform is of a width substantially less than the width of the stack to permit the longitudinal marginal edges of the bags to hang over the edges of the platform and to counteract the tendency of said edges to curl upwardly whereby the top of the stack will be substantially flat along said edges.

11. The combination as defined in claim 10 wherein provision is also made for positively engaging the tops of the marginal edges of the stack at the mouth portion thereof to assure that said edges will lie flat preparatory to the opening operation.

12. In a packaging machine, in combination, means for supporting and elevating a stack of flat bags, each bag having an upper wall and a lower wall forming a two-ply portion and an extended flap forming a single-ply portion at the mouth of the bag, means for opening and withdrawing successive uppermost bags from the stack, said bag supporting means including a vertically movable elevating structure having means for supporting the single-ply portion of the stack, stop means engageable with the top of said single-ply portion, and means carried by and bodily movable vertically relative to said vertically movable elevating structure and said single-ply support arranged to support the two-ply portion of the stack and automatically maintain the top of the two-ply portion of the stack in a horizontal plane substantially level with the top of said single-ply portion during withdrawal of successive bags therefrom.

13. In a packaging machine, in combination, means for supporting and elevating a stack of flat bags, each bag having an upper wall and a lower wall forming a two-ply portion and an extended flap forming a single-ply portion at the mouth of the bag, means for opening and withdrawing successive uppermost bags from the stack, said bag supporting means including a vertically movable elevating structure having means for supporting the single-ply portion of the stack, stop means engageable with the top of said single-ply portion, and means including a platform carried by and bodily movable vertically relative to said vertically movable elevating structure and said single-ply support arranged to support the two-ply portion of the stack independently of said single-ply portion and to automatically maintain the top of the two-ply portion of the stack in a horizontal plane substantially level with the top of said single-ply portion during withdrawal of successive bags therefrom, the vertical movement of said platform upwardly relative to said single-ply support corresponding substantially to the reduction in height of the two-ply portion of the stack during such withdrawals.

14. The combination as defined in claim 12 wherein the elevating structure is mounted for vertical movement and includes means for resiliently urging the structure upwardly to maintain the top of the single-ply portion of the stack in engagement with said stop means in bag opening position, said resilient means providing a uniform tension against said stop as the weight of the stack is reduced by continued withdrawals therefrom.

15. The combination as defined in claim 12 wherein the bag opening means includes means frictionally engageable with the upper wall of the bag to break the adherence thereof to the lower wall prior to opening of the bag, and means for humping the top of the stack at a point adjacent the mouth of the bag to be engaged by said frictional means.

16. In a packaging machine, in combination, means for supporting and elevating a stack of flat bags, each having an upper wall and a lower wall forming a two-

ply portion and an extended flap forming a single-ply portion at the mouth of the bag, means for opening and withdrawing successive uppermost bags from the stack including a longitudinally reciprocable element frictionally engageable with the upper wall of the bag for breaking the adherence of the upper wall to the lower wall prior to opening the bag, said bag supporting means including means for humping the top of the stack at a point adjacent the mouth of the bag for cooperating with said frictionally engageable element.

17. In a packaging machine, in combination, means for supporting and elevating a stack of flat bags, each bag having an upper wall and a lower wall forming a two-ply portion and an extended flap from the lower wall forming a single-ply portion at the mouth of the bag leaving the edge of said upper wall free and exposed, means carried by said stack supporting means extended through openings in said flaps for retaining the bags on said supporting means until forcibly withdrawn therefrom, a pair of longitudinally reciprocable serrated elements frictionally engageable with the marginal portion of said exposed edge to break the adherence of the upper wall to the lower wall preparatory to opening the bag, said bag supporting and elevating means including an elevating structure having means for supporting the single-ply portion of the stack, stop means engageable with the top of the single-ply portion of the stack, and means carried by and bodily movable vertically relative to said elevating structure arranged to support and maintain the top of the two-ply portion of the stack in a horizontal plane substantially level with the top of said single-ply portion during withdrawal of successive bags therefrom.

18. The combination defined in claim 17 wherein the means for supporting the two-ply portion of the stack comprises a platform having a projection in the upper face thereof causing the stack to hump at a point adjacent said exposed edge for cooperation with said serrated elements.

19. The combination as defined in claim 18 wherein the retaining means comprises a U-shaped member having vertical legs extended through said openings, said stop member having a grooved portion for receiving the horizontal leg of the retaining member, and means for detachably retaining the horizontal leg in said groove.
